UNITED STATES PATENT OFFICE.

GUSTAVUS WILFORD ANDERSON, OF BLOOMINGTON, ILLINOIS.

WALL-SAFE.

No. 891,969.

Specification of Letters Patent. Patented June 30, 1908.

Application filed January 22, 1908. Serial No. 412,180.

To all whom it may concern:

Be it known that I, GUSTAVUS WILFORD ANDERSON, a citizen of the United States, residing at Bloomington, in the county of McLean and State of Illinois, have invented 5 a new and useful Wall-Safe, of which the following is a specification.

This invention relates to wall safes.

The object of the invention is to provide, 10 as an article of manufacture, a safe of the character described provided with lugs to hold a fire-proof material on all six sides thereof, and other lugs embedded in the fire-proof material but free from the safe body to 15 attach the same to a wall.

With the above and other objects in view, as will appear as the nature of the invention is better understood, the same consists in the 20 novel construction and combination of parts of a wall safe, as will be hereinafter fully described and claimed.

In the accompanying drawings forming a part of this specification, and in which like characters of reference indicate corresponding parts, Figure 1 is a view in perspective of the safe showing the same before its parts are assembled. Fig. 2 is a perspective view of the safe, partly in section, showing it as it appears when ready to be positioned in a 25 wall. Fig. 3 is a fragmentary detail view in perspective of the door hinge. Fig. 4 is a perspective detail view of the bracket or anchoring member that may be employed in securing the safe in the wall of a frame building. Fig. 5 is a fragmentary detail view 30 showing the means employed for securing the safe in position when used in a frame building.

The safe comprises a rectangular body or 35 shell 1 of cast iron or steel, a back plate 2 integral with the shell, a front plate 3, which is provided with a circular door seat 4, and a door 5.

The shell is provided with a forwardly projecting lug 6 at each of its four corners that are adapted to engage orifices 7 in the four corners of the front plate, these lugs being upset to insure a positive assemblage of the plate with the shell. In addition, the front 45 plate is provided with a flange 8 that projects at right angles to its inner face and defines a socket in which the front end of the shell is seated.

The door seat is internally double cone-shaped and the door 5 is externally double cone-shaped, the object of this arrangement

being to provide a close fit between the door and seat to preclude the feeding of powder or other explosive between the meeting edges of the parts. Extending from one side of the door seat is a hollow extension 9, which is approximately rectangular in shape, as shown in Fig. 3, and in which fits a hinge member 10 carried by the door 5, a pin 11 passing through the extension and through 60 the member 10, serving to hold the parts positively assembled. The construction of hinge shown will allow the door to be swung entirely away from its opening. The outer face of the door and of the hinge member lie 65 flush with the outer rim of the seat, as shown in Fig. 2, so that when the safe is positioned within a wall, no projecting parts will be seen. The door carries a knob 12 of an ordinary combination lock. 75

In order to render the body of the safe, formed by the shell and the front and rear plates, fireproof, the same is inclosed in a body of fireproof cement 13 which may be of any thickness, and lies flush with the outer 80 edge of the door seat, it being understood that all six sides of the safe are similarly inclosed. In order to cause the cement shell to be firmly anchored to the body, the latter is provided adjacent to its rear end and upon 85 its upper and lower sides with lugs 14, of which any number may be employed. These lugs will be inclosed in cement and will thus serve to hold the latter positively in position. In addition to the lugs, wire netting 15 is 90 employed to reinforce the cement, and which is embedded therein and is thus hidden from view. After the safe has been arranged within the wall, flush with the plastering, its outer face is papered over, so that only the 95 combination knob will be exposed to view.

Where the safe is to be anchored within the walls of a frame structure, a plurality of brackets are employed, one of which is shown in detail in Fig. 4. Each of these brackets 100 comprises a plate 16 provided with a plurality of orifices 17, and at its terminals with pairs of studs or projections 18 that are disposed at right angles to each other, are approximately flat, preferably longitudinally 105 fluted, and are designed to be sunk into the corners of the cement shield 13 before the same is set. These brackets will be secured to the adjacent studdings of the building in which the safe is located, and any desired 110 number may be employed.

The improvements herein defined are sim-

ple in character, but will be found thoroughly effective for the purposes designed and will combine in providing a highly efficient and reliable form of wall safe.

5 I claim:—

As an article of manufacture, a wall safe having a substantially rectangular body provided with projecting lugs and a front plate having an annular door casing projecting 10 therefrom, a door held in said casing, fire-proof material surrounding said body and front plate on all six sides, said fire-proof material being flush with the projecting door

casing and entirely covering the lugs on the body, and other lugs embedded in the fire-proof material provided with openings to receive bolts or screws for securing said safe to a wall.

In testimony that I claim the foregoing as my own, I have hereto affixed my signature 20 in the presence of two witnesses.

GUSTAVUS WILFORD ANDERSON.
